UNITED STATES PATENT OFFICE.

JOSEPH AMBROSE, OF DETROIT, MICHIGAN, ASSIGNOR TO MICHIGAN SMELTING AND REFINING COMPANY, OF DETROIT, MICHIGAN, A CORPORATION OF MICHIGAN.

DIE-CASTING MACHINE.

Application filed January 24, 1921. Serial No. 439,538.

To all whom it may concern:

Be it known that I, JOSEPH AMBROSE, a citizen of the United States of America, residing at Detroit, in the county of Wayne 5 and State of Michigan, have invented certain new and useful Improvements in Die-Casting Machines, of which the following is a specification, reference being had thereto in the accompanying drawings.

10 The invention relates to die casting machines and has for one of its objects the provision of means movable with a mold section when being separated from another mold section for withdrawing the gate from 15 the other mold section. Another object is the provision of yieldable means for forcing the inner mold section away from the pot for a limited distance to facilitate movement of the same with the outer mold section. Further objects reside in forming 20 the pot with a cylindrical portion which is engageable by cylinders of different internal diameters and in which pistons of corresponding diameters slidably engage for 25 forcing the metal from the pot into the mold; also in the provision of an apron secured to the cylindrical portion of the pot above the aperture in its wall and extending downwardly into the molten metal, 30 whereby the dross is prevented from entering through the aperture and being subsequently forced into the mold. The invention resides in still other features of construction and novel arrangements and combinations of parts as more fully hereinafter 35 set forth.

In the drawings:

Figure 1 is a top plan view partly in section of a die casting machine embodying 40 my invention;

Figure 2 is a longitudinal central sectional central sectional view, partly in elevation, thereof;

Figure 3 is an end view thereof;

Figure 4 is a cross section on the line 4-4 of Figure 1;

Figure 5 is an enlarged sectional view of the mold sections and holders, partly in elevation;

50 Figures 6 and 7 are respectively a side elevation of a plunger and a longitudinally central cross section through a cylinder of different effective diameters from the corresponding parts shown in Figure 2.

55 1 is a pot containing the molten metal and

provided with the nozzle 2 and the pump 3 for forcing the molten metal in predetermined amounts through the nozzle, 4 is a sectional mold, which in the present instance, comprises the inner die block 5 and 60 outer die block 6 which cooperate to form the cavity 7. 8 is the holder for the inner die block and 9 the holder for the outer die block, the inner die block having the projection 10 with the passageway 11 there-through for placing the cavity 7 in communication with the nozzle 2. This projection extends through the holder 8 and preferably has the spherical recess 12 in its end which is adapted to be fitted in by the 70 spherical end 13 of the nozzle.

The holders 8 and 9 slidably engage at their opposite ends the parallel horizontally extending rods 14 which extend from the pot 1 through the stationary end frame 75 member 15 to which they are secured as by means of the nuts 16. 17 is a suitable standard having the bearings 18 for engaging the rods, this standard being inside the end frame member 15.

80 For moving the inner and outer die blocks relative to the nozzle 2 there is the non-revolvble screw 19 which is fixedly secured at its inner end to the outer die block holder 9, and threadedly engaged by the 85 collar 20 passing through the end frame member 15. For preventing the collar 20 from moving longitudinally, the same has the shoulders 21 and 22 at opposite sides of 90 the end frame member and to permit of easy rotation of the collar, suitable anti-friction bearings 23 are provided between the shoulders and the end frame member. 24 is a worm wheel non-rotatably secured to the collar 20 and engaged by the worm 95 25 upon the vertically extending drive shaft 26, which latter is suitably driven from the electrical motor 27.

100 With the construction as thus far described, upon rotation of the collar 20 in the proper direction, the screw 19 will be longitudinally moved inward, thereby moving the inner and outer die block holders 8 and 9 respectively as well as their die blocks 5 and 6 until the projection 10 firmly 105 engages the end of the nozzle 2.

Upon actuation of the pump 3, molten metal is forced through the nozzle 2 and passageway 11 into the cavity 7 formed by the die blocks after which the die blocks 110

are moved horizontally away from the nozzle. In order to facilitate the simultaneous outward movement of both the die blocks for a limited distance, there are coil 5 springs 28 surrounding the inner ends of the rods 14 and abutting the pot 1 and the inner die block holder 8, these coil springs being under compression when the parts are in position, to receive the molten metal. 10 Upon continued outward movement of the screw 19, the inner die block with its holder, continue to move outwardly with the outer die block and its holder due to the friction between the casting and its gate upon the 15 side walls of the cavity and the passageway leading thereto. To separate the outer die block from the inner die block, stops 29 are provided, secured to the pot 1 and slidably engaging the ends of the inner die block 20 holder 8, these stops having the heads 30 at their outer ends for engaging the ends of the inner die block holder and limiting its outward movement.

In order to remove the gate from the 25 passageway 11, the latter is inwardly flared and there is a pin 31 pivotally secured to the holder 9 as at 32. This pin extends through the outer die block and inner die block into the passageway 11 and has a 30 cross section at its free end providing clearance in the passageway for the passage of the molten metal into the cavity within the die blocks. Thus after the inner die block holder 8 has engaged the heads 30 of the 35 stops 29 and upon continued outward movement of the outer die block with its holder, the pin 31 engaging the gate which has solidified, withdraws the same from the passageway 11 and away from the inner die 40 block so that after the casting has been removed, the parts are again ready to be moved inwardly to be in position for the next casting operation.

To maintain the metal in the pot 1 in 45 molten state, suitable burners 33 are provided therebeneath, and to prevent blocking of the nozzle 2 by metal which has solidified, the nozzle is upwardly inclined and a burner is located beneath its upper end. 50 The spherical end section 34 of the nozzle also has its passageway upwardly inclined so that any molten metal which does not remain in the cavity 7 between the die blocks or in the passageway 11, will flow 55 back into the molten metal in the nozzle.

For the purpose of pumping different amounts of molten metal through the nozzle, depending upon the size of the cavity within the die blocks, I have provided the pot 60 1 with the upwardly extending cylindrical portion 35 which is adapted to interchangeably receive cylinders of different internal diameters. As shown in Figures 1 and 2, the cylinder 36 has a wall of less thickness 65 than the wall of the cylinder 37 shown in

Figure 7, and consequently, the piston 38 shown in Figures 1 and 2 is of greater diameter than the piston 39 shown in Figure 6, so that the pump shown in Figures 1 and 2 forces a greater amount of molten metal into the mold cavity upon each downward stroke of the piston than the pump comprising the cylinder and piston shown respectively in Figures 7 and 6. The cylindrical portion 35 has the annular flange 70 40 at its upper end and the pump cylinders also have annular flanges 41 at their upper ends. Cap bolts 42 engaging these flanges, secure the cylinders to the cylindrical portion, and for readily removing the cylinders from the cylindrical portion, other cap bolts 43 are provided threadedly engaging the flanges of the cylinders, but abutting the flanges of the cylindrical portion so that upon proper rotation of these latter cap bolts after the former have been disengaged, the cylinders are moved outwardly relative to the cylindrical portions, the walls of these parts being preferably provided with a draft to permit of the more easy engagement and disengagement of the same. 90

To prevent the entrance of dross into the pump, the cylindrical portion 35 has the aperture 44 near its upper end and below the normal level of the molten metal in the pot and also has the apron 45 extending from its top downwardly into the molten metal, so that any molten metal entering within the pump cylinder through the aperture 46 in its wall registering with the aperture 44 in the wall of the cylindrical portion must pass beneath the lower end of the apron. 95

The lever 47 for actuating the pump plunger may be connected to extend in several 100 different directions to make the same more accessible for operation. As shown, projections 48 are formed upon the apron to which the link 49 may be pivotally connected at its lower end. The lever 47 has one end pivotally connected to the upper end of this link and has an intermediate portion pivotally connected to the link 50 in turn pivotally connected to the piston. By disconnecting the lower end of the link 49, the same may be rotatively adjusted and connected to another projection, thereby 105 changing the position of the lever. 110

What I claim as my invention is:

1. The combination with a nozzle for the passage of molten metal, of a sectional mold, a passageway for placing the cavity within said mold in communication with said nozzle, means for moving said sectional mold bodily away from said nozzle, stationary means for subsequently separating the mold sections, and means movable with one of the mold sections for moving the gate from said passageway during the separation of the mold sections. 115

120

125

130

2. The combination with a nozzle for the passage of molten metal, of inner and outer cooperating die blocks, a passageway for placing the cavity within said die blocks into communication with said nozzle, means for simultaneously withdrawing said inner and outer die blocks from said nozzle, stationary means for subsequently withdrawing said outer die block from said inner die block, and means movable with said outer die block for withdrawing the gate from said passageway. 6 70
3. The combination with a nozzle for the passage of molten metal, of a pair of inner and outer cooperating die blocks, means secured to said outer die block for moving both of said die blocks toward and away from said nozzle, and means for yieldably moving said inner die block away from said nozzle a limited distance. 15 75
4. The combination with a nozzle for the passage of molten metal, of a pair of inner and outer cooperating die blocks, means secured to said outer die block for moving both of said die blocks toward and away from said nozzle, resilient means for moving said inner die block away from said nozzle, a limited distance, and means for limiting the outward movement of said inner die block whereby upon continued outward movement of said outer die block separation will occur. 20 80
5. The combination with a nozzle for the passage of molten metal, of a pair of cooperating outer and inner die blocks, holders for said die blocks, a longitudinally movable member secured to said outer die block for moving both of said die blocks toward and away from said nozzle, means for guiding said holders in their movement, resilient means for forcing the holder for said inner die block away from said nozzle a limited distance, and stops engageable by said last mentioned holder for limiting its movement away from said nozzle. 25 85
6. The combination with a nozzle for the passage of molten metal, of a pair of cooperating outer and inner die blocks, holders for said die blocks, a longitudinally movable member secured to said outer die block for moving both of said die blocks toward and away from said nozzle, means for guiding said holders in their movements, resilient means for forcing the holder for said inner die block away from said nozzle a limited distance, and stops engageable by said last mentioned holder for limiting its movement away from said nozzle, and a pin movable with said outer die block and engaging the gate for withdrawing the latter from said inner die block upon continued movement of said outer die block away from said nozzle. 30 90
7. The combination with a pair of cooperating die blocks, of a threaded rod non- 35 95
- rotatably secured to one of said die blocks for moving the same toward and away from the other of said die blocks, a rotatable collar threadedly engaging said rod and power driven means for rotating said collar. 70
8. The combination with a pot containing molten metal, of a pair of cooperating die blocks, a threaded rod fixedly secured to one of said die blocks for moving said die blocks toward and away from said pot, a stationary frame member, a collar threadedly engaging said rod and extending through said frame member, said frame member, anti-friction bearings between said frame member and shoulders, and power driven means for rotating said collar. 75 80
9. The combination with a pot containing molten metal and having an upwardly inclined nozzle portion and a cylinder receiving portion, of a cylinder insertable within said cylinder receiving portion and detachably secured thereto, a plunger longitudinally movable within said cylinder, said cylinder receiving portion and said cylinder being provided with means for placing the interior of said cylinder in communication with the space in said pot outside of said cylinder receiving portion. 85 90
10. The combination with a pot containing molten metal and having an upwardly inclined nozzle portion and a cylinder receiving portion, of a cylinder insertable within said cylinder receiving portion, a plunger longitudinally movable within said cylinder, means for placing the interior of said cylinder in communication with the space in said receptacle outside of said cylinder receiving portion, means for securing said cylinder to said cylinder receiving portion, and means for forcing said cylinder out of said cylinder receiving portion. 95 100
11. The combination with a pot containing molten metal and having an upwardly extending cylindrical portion with an aperture near its upper end, of a plunger longitudinally movable within said cylindrical portion, and an apron secured to said cylindrical portion above said aperture and extending downwardly into the molten metal below the said aperture for preventing the entrance of dross into said aperture. 110 115
12. The combination with a pot containing molten metal and having an upwardly extending cylindrical portion with an aperture near its upper end, of a plunger longitudinally movable within said cylindrical portion, and an apron spaced from said cylindrical portion and extending below the said aperture for preventing the entrance of dross into said aperture. 120 125
13. The combination with a nozzle for the passage of molten metal, of a sectional mold, a passage-way for placing the cavity within said mold in communication with said nozzle. 130

zle, means for moving said sectional mold bodily away from said nozzle, and stationary means for substantially separating the mold sections.

5 14. The combination with a pot containing molten metal and having an upwardly inclined nozzle portion and a cylinder receiving portion, of a cylinder insertable within said cylinder receiving portion, and

a plunger longitudinally movable within said cylinder, said cylinder receiving portion and said cylinder having registering openings formed therein for placing the interior of said cylinder in communication with the space in said pot outside of said cylinder receiving portion.

In testimony whereof I affix my signature.
JOSEPH AMBROSE.
